W.S. ATTORNEY.

UNITED STATES PATENT OFFICE

WILLIAM NEUSÜS, OF YORKVILLE, ILLINOIS

FIRE ESCAPE

Application filed July 30, 1929. Serial No. 382,189.

This invention relates to certain novel improvements in fire escapes and has for its principal object the provision of an improved construction of this character which will be efficient and positive in use and economical in manufacture.

It is among the objects of my invention to provide a device which may be secured to the side of a building or the like adjacent openings thereto, such as for example windows, so as to provide an escape during a fire or the like.

Another object of the invention is to provide a device of the above described character which will normally be disposed in an inoperative position.

Another object of the invention is to provide a device of the above described character which will be arranged so that it may be very quickly moved into an operative position.

A further object of the invention is to provide a device of the above described character which will be so constructed that when inoperative access thereto may only be attained by an authorized person or from the interior of the building with which it is associated.

A still further object of the invention is to provide a device of the above described character which will be so arranged that it will not be possible to use the same to attain access into the building with which it is associated when the device is arranged in inoperative position.

A still further object of the invention is to provide a device with which a portion may be associated so that an enclosed structure may be provided.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is an elevational view depicting a preferred form of construction of my invention associated with a building;

Fig. 2 is a view looking in the same direc-

tion as Fig. 1 depicting the preferred embodiment of my invention in partially open position;

Fig. 3 is a sectional view taken substantially on the line 3—3 on Fig. 2;

Fig. 4 is a sectional view taken substantially on the line 4—4 on Fig. 2;

Fig. 5 is a detail view of a hinge construction employed in the device;

Fig. 6 is a sectional view taken substantially on the line 6—6 on Fig. 5;

Fig. 7 is a sectional view taken substantially on the line 7—7 on Fig. 2;

Fig. 8 is a sectional view taken substantially on the line 8—8 on Fig. 7;

Fig. 9 is a transverse sectional view depicting a modified form of construction for the device;

Fig. 10 is an elevational view depicting a portion of the device as illustrated in Fig. 9;

Fig. 11 is a sectional view depicting the latching arrangement employed in my device; and

Fig. 12 is a typical wiring diagram of alarm arrangement employed in the device.

In the accompanying drawings wherein I have illustrated the preferred form of construction for my invention 10 generically indicates the wall of a building which has openings therein such as the windows 11 and 12. The windows 11 and 12 are vertically aligned and are intended to co-operate with the different floors of the building of which the wall 10 provides a part. While in the drawings I have depicted the device as being associated with a two floored building it is to be understood that the device might be associated with a building of any desired number of floors and this would still be within the spirit and scope of my invention.

Arranged to extend parallel to the wall 10 is a wall 13 of the container generically indicated by 14. The side of the container 14 opposite the wall 13 is preferably open and is closed by a cover member 15. On the side wall 16 of the container 14 I mount one of the leaves of hinge constructions generically indicated by 17. The other of the leaves of the hinge constructions is secured to the cover 15 and in this manner the cover 15 is hingedly

55

60

65

70

75

80

85

90

95

100

mounted so as to be movable to and from closing position with respect to the open side of the container 14. Secured to the wall 10 are the portions 18 of hinge constructions 5 generically indicated by 19, the other portions 20 of the hinge constructions 19 being secured to the side wall 21 of the container 14, which side wall 21 is arranged opposite the side wall 16. A pintle 22 interconnects 10 the portions 18 and 20 of the hinge constructions 19 and it is, therefore, manifest that the container 14 is hingedly mounted so that the wall 13 may either be disposed parallel to the wall 10 as illustrated in full lines in 15 Fig. 4 or so that the wall 13 may be moved into the dotted line position of Fig. 4, in which position said wall is substantially at right angles with the wall 10. Depending from the lower side of the portion 20 of the 20 hinge structure 19 is a lug 23 which normally rests on the upper surface of the portion 18 and in the upper surface of the portion 18 I provide a recess 24. When the wall 13 is arranged parallel to the wall 10 25 as illustrated in full lines in Fig. 4 the lower surface of the lug 23 rests on the upper surface of the portion 18. However, when the container 14 is moved into the dotted line position of Fig. 4 so that the wall 14 is substantially at right angles to the wall 10 the lug 23 is positioned so that it may enter into the recess 24 and in this manner 30 the container 14 is held in the dotted line position of Fig. 4. In the present instance 35 I have provided two hinge structures such as 19 but it is to be understood that any greater number might be provided dependent upon the requirements and this will still be within the spirit and scope of my 40 invention.

Substantially midway between the hinges 19 I provide a member 25 which is secured to the wall 10. Brackets 26 and 27 are secured to the wall 21 and extend outwardly over the 45 member 25, which member 25 is substantially U-shaped. Between the limb portions of the U-shaped member 25 a pintle 28 is secured which is secured to the brackets 26 and 27. Disposed around the pintle 28 in the member 50 25 is a coil spring 29, one end of which is secured to the member 25 and the other end of which is secured to the pintle 28. The coil spring 29 acts on the pintle 28 and the brackets 26 and 27 and, therefore, the 55 container 14 to normally urge the container from the full line position in Fig. 4 into the dotted line position of this view. A similar arrangement generically indicated by 30 is arranged intermediate the hinge structure 17 60 and the spring in the structure 30 normally acts on the cover 15 to tend to move the cover 15 from closing position with respect to the open side of the container 14 into the position in which it is depicted in Fig. 4, a suitable arrangement being provided for limit- 65

ing the movement of the cover 15 so as to retain the same in the position depicted in Fig. 4 and this arrangement may be similar to that depicted in Figs. 5 and 6 for the hinge structures 19.

In order to retain the cover member 15 and the container 14 against the actions of the springs acting thereon I provide the following latching arrangement. Extended through the wall 10 in juxtaposition to the windows 11 and 12 are shafts 31 and 32. Either interiorly of the wall 10 or exteriorly thereof, as disclosed in Fig. 3, the shafts 31 and 32 are interconnected, this being carried out in the present instance by extending a 70 chain 33 between sprockets on these shafts. As best illustrated in Fig. 11 a lug 34 is provided on the cover 15. On the inner end of the shaft 31 I provide a retaining lug 35. When the cover member 15 is in closing position 75 the lug 35 is disposed behind the foot portion on the lug 34 and normally holds the cover member 15 in closing position. In the rear wall 13 of the container 14 I provide a slot 36 through which the shaft 31 is extended. The slot 36 is horizontally disposed and extended therefrom at right angles thereto and communicating therewith is an opening 37. On the shaft 31 adjacent the wall 13 is a retaining lug 38, which retaining lug is 80 mounted on the shaft 31 so as to be disposed 90° behind the position of the lug 35. Under normal conditions when the cover 15 is in 85 closed position and the wall member 13 is arranged parallel to the wall 10 the device is 90 inoperative. However, by rotating either the shaft 32 or 31 the lug 35 may be moved from 95 retaining position with respect to the lug 34 and this will permit the spring in the structure 30 to move the cover 15 into the position 100 depicted in Fig. 4. By reason of the fact that the lug 38 is disposed 90° behind the lug 35 the container 14 will not be released until 105 either the shaft 31 or 32 has been further rotated so as to bring the lug 38 into alignment with the opening 37. As soon as the lug 38 moves into alignment with the opening 37 the spring 28 will pivot the container 14 by 110 reason of the fact that the lug 38 is smaller than the opening 37 and will, therefore, no longer bear on the wall 13 so as to hold the 115 container 14 against the action of the spring 28 on the container 14 and the lug 23 is moved into the recess 24 and, therefore, the container 14 will be stopped in the position indicated by 120 dotted lines in Fig. 4.

On the inner surface of each of the walls 16 and 21 I provide a plurality of studs. The studs on the wall 16 are indicated by 39 while the studs on the wall 21 are indicated by 40. Pivotaly mounted on the studs 39 are the dogs 41 and pivotaly mounted on the studs 40 are the dogs 42. The studs 39 and 40 are arranged in transverse alignment with each other. Therefore, rods 43 may be extended between 130

the outer ends of the dogs 41 and 42. Shoulders 44 are defined on the dogs 41 and 42 which shoulders bear against the wall 13 so as to limit the pivotal movement of the dogs 41 and 42 about the studs 39 and 40 and this engagement of the shoulders 44 with the wall 13 limits the position of the rods 43 so that a ladder like formation is provided. A link 45 is pivotally attached to each of the dogs 41 as indicated at 46 and, therefore, the structures mounted on the studs 39 and 40 move as a unit and in this manner a ladder like arrangement is provided. When the cover 15 is in closing position it bears against the structures mounted on the studs 39 and 40 and retains them interiorly of the container 14. However, when the cover 15 moves to open position the structures mounted on these studs pivot forwardly so as to provide the ladder like arrangement set forth.

In use the device is mounted on the side of a building so that the container 14 will be juxtaposed the windows 11 and 12 as clearly illustrated in Fig. 1. In the event of a fire or other emergencies either the shaft 31 or 32 is rotated in the manner set forth so as to first release the cover 15 which releases the structures mounted on the studs 39 and 40, and then further rotation of either of the shafts 31 or 32 will position the container 14 in the dotted line position of Fig. 4. In this position access to the structures mounted on the studs 39 and 40 may be attained through either of the windows 11 or 12 and, therefore, the device may be used as a fire escape or the like.

It is manifest that the cover 15 will afford a protection about the ladder like arrangement in combination with the wall 10. However, under certain conditions it may be desirable to provide an arrangement so that the ladder like arrangement will be substantially enclosed and this can be accomplished by providing the following arrangement. The cover 15 will preferably be arranged so that it embodies flanges around the edges thereof. A frame generically indicated by 47 would be provided and the area enclosed by this frame would be covered with a suitable fire proof material, as for example asbestos impregnated wire, this latter being used so as to afford greater rigidity. The frame 47 would be hinged as indicated at 48 so as to normally be disposed interiorly of the cover 15 and would be moved into the position illustrated in Fig. 9 when needed.

If desired a switch structure generically indicated by 49 can be mounted on the wall 16, which switch structure would include an operating arm 50 (Figs. 3 and 4) that would normally bear against the cover when the cover was in closed position and when the cover would be moved into the open position illustrated this switch 49 would operate to close an electric circuit to a suitable alarm

device 51. This arrangement could advantageously be employed in connection with structures extending to more than two floors where it would be extremely desirable to provide an alarm when the device was operated.

It is manifest that since the device can be operated only from the interior of the building with which it is associated that the device will not be accessible for use to make unauthorized entrances into the building although, if desired, an arrangement might be provided which would require a secret knowledge for the operation thereof which would permit the operation of the device from the exterior of the building. It is apparent that the device might be very effectively manufactured and installed and will, therefore, very efficiently accomplish the result intended.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In combination with a building, a housing, a cover member hingedly connected to said housing, means for normally urging said cover member into open position with respect to said housing, means for hingedly connecting said housing to said building, means for urging said housing into a predetermined position relative to said building, means for resisting the action of said last named means, means providing a ladder structure mounted in said housing, and means for holding said cover member in closed position.

2. In combination with a building, a housing having an open side, a cover member hingedly connected to said housing over said open side, elements on said cover member, means for hingedly connecting said housing to said building, means for urging said housing into a predetermined position relative to said building, means for resisting the action of said last named means, means providing a ladder structure mounted in said housing, means for normally urging said cover member into open position, and releasable means for restraining the action of said last named means, said releasable means including rotatable rods extended through said housing and the wall of said building so as to be accessible from the interior of said building, and means on said rods engaging said elements on said cover member to hold said cover member normally in closed position.

3. In combination with a building, a housing having an open side, a cover member hingedly connected to said housing over said open side, elements on said cover member, means for hingedly connecting said housing to said building, means for urging said housing into a predetermined position relative to said building, means for resisting the action of said last named means, means providing a ladder structure mounted in said housing, means for normally urging said cover member into open position, releasable means for restraining the action of said last named means, said releasable means including rotatable rods extended through said housing and the wall of said building so as to be accessible from the interior of said building, means on said rods engaging said elements on said cover member to hold said cover member normally in closed position, and means on the inner side of said housing for operating an alarm circuit when said cover member is moved into open position, said last named means including arms normally retained in open circuit position by engagement of said cover member.
- 10 4. In combination with a building, a housing having an open side, a cover member hingedly connected to said housing over said open side, elements on said cover member, means for hingedly connecting said housing to said building, means for urging said housing into a predetermined position relative to said building, means for resisting the action of said last named means, means providing a ladder structure mounted in said housing, means for normally urging said cover member into open position, to permit said ladder structure to be moved into operative position, said cover member when in closed position retaining said ladder structure in inoperative position, and releasable means for restraining the action of said last named means, said releasable means including rotatable rods extended through said housing and the wall of said building so as to be accessible from the interior of said building, and means on said rods engaging said elements on said cover member to hold said cover member normally in closed position.
- 15 5. In combination with a building, a housing having an open side, a cover member hingedly connected to said housing over said open side, elements on said cover member, means for hingedly connecting said housing to said building, means for urging said housing into a predetermined position relative to said building, means for resisting the action of said last named means, means providing a ladder structure mounted in said housing, means for normally urging said cover member into open position, releasable means

for restraining the action of said last named means, said releasable means including rotatable rods extended through said housing and the wall of said building so as to be accessible from the interior of said building, means on said rods engaging said elements on said cover member to hold said cover member normally in closed position, and means on the inner side of said housing for operating an alarm circuit when said cover member is moved into open position, said last named means including arms normally retained in open circuit position by engagement of said cover member.

10 15 20 25 30 35 40 45 50 55 60 65 70 75 80 85 90 95 100 105 110 115 120 125 130

In testimony whereof I affix my signature.

WILLIAM NEUSÜS.
